SNUBBED SPRING GROUP

Robert B. Cottrell, Chicago, Ill., assignor to
American Steel Foundries, Chicago, Ill., a corporation of New Jersey

Application December 7, 1950, Serial No. 199,601

9 Claims. (Cl. 267—9)

1
This invention relates to a spring package and more particularly to a construction involving spaced spring plates with coil springs and a novel friction device therebetween.

The principal object of the invention is to provide a novel friction device which will fit within the space limitations inherent in such a package and which will provide adequate capacity for controlling relative movements between the top and bottom plates and snubbing synchronous oscillations of the spring group.

A more specific object of the invention is to provide a floating friction assembly which will yieldingly resist sidewise movements between the top and bottom portions of the spring group without imposing excessive stresses on the parts of the snubbing or friction device and its connections with the top and bottom plates.

Another object of the invention is to provide a novel spring group wherein the parts of the friction device are arranged to obtain maximum spring capacity for actuating the device without encroaching on the space for the load coils or reducing the strength of the package.

These and other objects of the invention will become more apparent from the specification and the drawings, wherein:

Figure 1 is a top plan view of the novel spring package, one half of the top portion of the package being removed to more clearly illustrate the construction of the bottom portion.

Figure 2 is an end view, partly in section on the line 2—2 of Figure 1; and

Figure 3 is a side elevational view of the package.

Describing the invention in detail, the spring package comprises spaced top and bottom plates 2 and 4 of scalloplike form at their ends to conform to the contour of the springs 6, 6 confined therebetween adjacent opposite ends thereof. It will be seen that each set of springs comprises inner and outer coils and that four sets of springs are employed and located at the four corners. The top and bottom plates have inturned flanges 8, 8 arranged to conveniently confine the upper and lower ends of the springs 6, 6.

A friction device, generally indicated 10, is located centrally of the group between the springs 6, 6 at opposite ends of the group. The friction device comprises a friction casing, generally indicated 12, formed integral with the bottom plate, said casing comprising spaced generally parallel substantially vertical side walls 14, 14 at opposite sides thereof interconnected at opposite ends by spaced end walls 16, 16. The side walls and end

2
walls 14 and 16 form a substantially rectangular casing. The lateral edges of the end walls 16, 16 at their junctures with the side walls 14, 14 merge into adjacent portions 18, 18 of the flange 8 of the bottom plate. The portions 18, 18 converge inwardly on the adjacent side of the plate and are reinforced on their external sides by a substantially horizontal gusset 20 which merges with the lower edge of the related end wall 16. The bottom plate may be provided with spaced depending bosses 22 which are adapted to fit into a spring seat of a side frame or a spring plank. The friction casing or bottom follower 10 receives a stirrup or top follower, generally indicated 24, therein. The stirrup, top follower or carrier 24 comprises spaced substantially vertical side walls 26, 26 which are disposed alongside the walls 14, 14 of the friction casing and are spaced slightly inwardly therefrom in order to accommodate horizontal and canting movements between the top and bottom plates. The upper edges of the side walls 26, 26 merge with the underside of the top plate 2 and are connected at the upper ends of their external sides to hollow ribbing 28 which depends from the underside of the top plate and is designed to skirt around and extend between the adjacent sets of springs 6, 6 to form positioning means therefor. The ribbing 28 also strengthens the top plate. The lower edges of the side walls 26, 26 of the top follower are interconnected by a substantially horizontal generally flat wall 30 which provides on its top side a friction surface 32 (Figure 2) on which is supported a friction assembly generally designated 34.

The friction assembly 34 is disposed between the side walls 26, 26 and comprises at each end thereof a substantially triangular friction shoe 36, a troughlike wedge 38 which receives the lower ends of an actuating spring 40 therein, the upper end of the spring seating as at 42 against the underside of the top plate 2.

Each shoe comprises a bottom wall 44 which frictionally engages at its bottom side the friction surface 32 on the bottom wall of the stirrup. The outer edge of the wall 44 is connected to the lower end of a substantially vertical friction wall 46 of the shoe, the external side of the wall 46 having a friction surface 48, which engages as at 50 (Figure 3) a friction plate 52 mounted on the adjacent end wall 16 of the friction casing in any convenient manner preferably as by welding at 54, 54. The front wall 46 is connected adjacent to its upper end on its rear side with the upper end of a diagonal wall 56, the wall 56 merging at 55 its lower end with the rear extremity of the wall

44. The wall 56 on each shoe presents a wedge surface 58 sloping downwardly inwardly of the stirrup. Each surface 58 engages a surface 60 on the bottom side of a diagonal wall 62 on the adjacent end of the wedge 38. The lower ends of the walls 62, 62 of the wedge merge with opposite ends of a substantially horizontal wall 64 at the bottom of the wedge 38, the top side of wall 64 presenting a spring seat as at 66 for the lower end of the compression spring 40 which is compressed between the seat 66 and the top plate 2. The upper ends of the walls 62, 62 merge with the lower ends of substantially vertical end walls 68, 68 of the wedge. The wedge 38 is also provided with spaced side walls 70, 70, said side walls merging with the lateral edges of the walls 62, 62, 64 and 68, 68 and forming a pocket 72 therewith receiving the lower portion of the spring 40 therein.

In operation, the spring 40 urges the wedge 38 downwardly and the walls 62, 62 thereof into engagement along surfaces 60, 60 with the complementary surfaces 58, 58 on the diagonal walls 56, 56 of the shoes 36, 36. The shoes are urged downwardly and engage their bottom walls 44 with the surface 32. The shoes are wedged apart and caused to engage on the surfaces 48 of the front wall 46 thereof with the friction plates 52, 52 on the casing as at 50, 50. During lateral movement of wedge 38 as shown in Figure 3, the friction assembly 34 is slidably on the surface 32. Thus it will be seen that excessive stresses are eliminated due to the yielding character of the friction assembly. It will be seen that by arranging the wedge member 38 in the form of a trough the pressure imposed against the wedge member is located at a level which is adjacent to the lower portions of the friction shoes. This feature stabilizes the action of the wedge and also reduces to the minimum bending moments on the spring 40. In addition, a maximum length of spring is obtained and the leverage on the spring due to vertical canting of the wedge is greatly reduced.

I claim:

1. In a spring group, spaced top and bottom plates, coil springs and a friction device confined therebetween, said device comprising a friction casing on one of the plates, a stirrup on the other plate telescoping into the casing and providing a substantially horizontal friction surface at the end thereof remote from and facing said other plate, a pair of shoes disposed at opposite sides of said stirrup and in frictional engagement with said surface, a wedge member interposed between said shoes and in wedging engagement therewith, said wedge member being a hollow member and presenting a spring seat therein disposed substantially closer to said surface than to said other plate, and a single spring extending at one end into said hollow member and seated at one end against said seat and at its other end against the inner side of said other plate and compressed between the same.

2. In a spring group, spaced top and bottom plates, coil springs and a friction device therebetween, said friction device comprising a casing on said bottom plate presenting opposed substantially vertical friction surfaces therein, a stirrup on the top plate extending into said casing and having a substantially horizontal wall at the bottom end thereof presenting a friction face on the top side thereof, a shoe at each side of the stirrup and in frictional engagement on the bottom side thereof with said face and in substan-

tially vertical face engagement on its outer side with the adjacent surface, said shoes presenting at their inner sides diagonal wedge surfaces sloping downwardly, a wedge between said shoes having wedging surfaces at opposite ends thereof in wedge engagement with respective wedge surfaces of the shoes, said wedge presenting a spring seat therewithin located adjacent to the bottom extremities of the wedge surfaces thereon and a single vertical coil spring compressed between said seat and the bottom side of said plate, said spring seat being disposed adjacent to the bottom portions of said shoes.

3. In a spring group, spaced top and bottom plates, coil springs and a friction device therebetween, said device comprising a casing on the top side of said bottom plate, said casing presenting internal opposed substantially vertical friction surfaces, a carrier depending from said top plate and telescoping into said casing, said carrier comprising spaced substantially vertical side walls connected at their upper edges to the bottom side of said top plate, a substantially horizontal friction wall interconnecting the bottom edges of said side walls and presenting a friction face on the top side thereof, a shoe disposed against each surface and in frictional engagement with said face on the forward and bottom sides thereof respectively, said shoes presenting diagonal wedge surfaces on their internal sides converging downwardly, a troughlike wedge member interposed between said wedge surfaces and having wedging engagement at opposite ends thereof with said wedge surfaces, said wedge member being open through the top side thereof and presenting an internal spring seat on the bottom thereof, said spring seat being disposed at the level of the lower portions of said shoes, and a vertical spring extending into the wedge member and compressed between said seat and the underside of said top plate.

4. In a spring group for a railway car truck, spaced top and bottom plates, coil springs and a friction device therebetween, said friction device comprising a friction casing on the internal side of one of said plates, said casing presenting internal substantially vertical friction surfaces at opposite sides, a carrier connected to the other plate and telescoping into said casing, said carrier comprising a friction face at the end thereof adjacent to said casing and extending transversely of the axis of said device, a friction shoe engaging each surface and said face, a wedge member disposed between said shoes and in wedge engagement at opposite ends thereof with the shoes along surfaces converging toward the axis of said device, side wedge member being hollow and presenting an internal spring seat extending transaxially of the device, and a single coil spring located substantially centrally between said shoes and compressed between said seat and said other plate, said spring seat being located a maximum distance away from said other plate to accommodate a spring of maximum length and to effect a minimum bending moment on said spring.

5. In a spring group, spaced top and bottom plates, resilient means and a friction device therebetween, said friction device comprising a casing on the top side of the bottom plate with internal opposed friction surfaces, a carrier depending from the top plate and having a substantially horizontal bottom wall with a friction face on the top side thereof, a pair of shoes disposed one against each surface and having their bottom sides frictionally engaged with said face, said

shoes presenting downwardly converging wedge surfaces on their inner sides, a troughlike wedge member interposed between said shoes, said wedge member having a bottom spring seat wall disposed adjacent to the lower portions of said shoes, diagonal downwardly converging walls connected at their lower ends to opposite ends of said bottom spring seat wall, substantially vertical end walls at opposite ends of the wedge connected at their bottom ends with the upper ends of the respective diagonal walls, and spaced side walls at opposite sides of the wedge member connected to the lateral edges of said walls of the wedge member and defining a pocket therewith, said diagonal walls having complementary wedging engagement with the wedge surfaces of respective shoes, and a substantially vertical compressed coil spring having its lower portion extending into the wedge member and bearing at its lower end against the top side of said spring seat wall and having its upper end seated against the underside of said top plate.

6. In a spring group, spaced top and bottom plates, springs and a friction device therebetween, said device comprising telescoping top and bottom followers connected to respective plates, one of said followers presenting substantially vertical opposed friction surfaces, the other follower presenting a horizontal friction face carrying a pair of shoes in frictional engagement with said surfaces, a pressure member wedged between said shoes, and spring means compressed between said pressure member and the adjacent plate to clamp the shoes between said pressure member and said face, said pressure member having its pressure receiving areas disposed adjacent to the portions of the shoes closest to said friction face.

7. In a spring group, spaced top and bottom plates, coil springs and a friction device therebetween, said friction device comprising telescoping top and bottom followers connected to respective plates, one of said followers presenting opposed friction surfaces, the other follower presenting a horizontal friction face carrying friction shoes in engagement with said friction surfaces, a spring, and a wedge member engaged by said spring and positioned between said shoes urging the same into engagement with said surfaces and said friction face.

8. In a spring group, spaced top and bottom

plates, a friction device therebetween, means for urging said plates apart, said friction device comprising telescoping top and bottom followers connected to respective plates, said bottom follower presenting opposed internal friction surfaces, said top follower presenting a substantially horizontal upwardly facing friction face at its lower end, a pair of shoes seated on said face and disposed one against each surface, a hollow wedge member interposed between the shoes and in wedge engagement therewith, said wedge member presenting diagonal internal surfaces converging toward the bottom of said wedge member and a spring seat between the lower ends of said diagonal surfaces, said diagonal surfaces on the wedge member serving to maintain said spring on the spring seat and preventing the spring from shifting off the seat, whereby the load of the spring is always directed against the center of the wedge member.

9. In a spring group, spaced top and bottom plates, a coil spring and a friction device therebetween, said device comprising top and bottom followers, said bottom follower having spaced opposed friction surfaces, said top follower extending between said surfaces and presenting a horizontal upwardly facing friction face at its lower end, friction shoes at opposite sides of said top follower in frictional engagement with adjacent surfaces and said friction face, a wedge interposed between said shoes and in wedge engagement therewith, and a spring compressed between the wedge and said top plate, said wedge engaging said shoes along areas thereof extending from adjacent the top portions of the shoes to adjacent the bottom portions of the shoes, and said spring bearing against said wedge on an area of the wedge located adjacent to the bottom portions of said shoes.
